(57) **CLAIM**

The ornamental design for a paper roll holder, as shown and described.

DESCRIPTION

FIG. 1 is a front view of a First Embodiment of a paper roll holder, showing our new design;

FIG. 2 is a front perspective view thereof;

FIG. 3 is a side view thereof;

FIG. 4 is a front view of a Second Embodiment of a paper roll holder, showing our new design;

FIG. 5 is a front perspective view thereof;

FIG. 6 is a side view thereof;

FIG. 7 is a front view of a Third Embodiment of a paper roll holder, showing our new design;

FIG. 8 is a front perspective view thereof; and,

FIG. 9 is a side view thereof.

The broken lines in the drawings form environmental structure that form no part of the paper roll holder design to be patented.

The broken lines in the drawing views represents unclaimed environment only and forms no part of the claimed design.
